GRADE INDICATOR

William F. O'Connor, Fort Leavenworth, Kans.

Application April 4, 1941, Serial No. 386,902

1 Claim. (Cl. 33—215)

This invention appertains to new and useful improvements in the general art of geometric instruments and more particularly to an instrument for determining the exact degree of an inclination.

The principal object of the present invention is to provide a grade indicator which will be substantially exact in operation and which will not be susceptible to the development of ready defects.

Another important object of the invention is to provide an instrument of the character stated which will not be affected by weather conditions and which is of unique construction and positive action in operation.

These and various other important objects and advantages of the invention will become apparent to the reader of the following specification.

In the drawings:

Figure 1 represents a vertical sectional view through the casing of the indicator.

Figure 2 represents a transverse sectional view through the device.

Figure 3 is a vertical sectional view through the device and applied to an inclined surface.

Figure 4 is a sectional view taken substantially on line 4—4 of Figure 1.

Figure 5 is a perspective view of the supporting block.

Figure 6 is a perspective view of the pointer.

Figure 7 is a fragmentary front elevational view of the casing.

Referring to the drawings wherein like numerals designate like parts, it can be seen that the instrument consists of an elongated base 5 having the V-shaped groove 6 extending longitudinally in the bottom thereof.

Numeral 7 generally refers to a bell shaped casing overlapping the base 5 at its lower end and being secured to the base by suitable elements such as screws 8. This casing 7 is of narrow construction and includes the back wall 9 and the front wall 10.

An elongated block 11 provided with openings 12 therein is secured to the base 5 at the top side thereof by disposing suitable securing elements 13 through the said opening 12 and into the base 5.

One edge portion of the block 11 is provided with openings 14 for receiving securing elements whereby the upstanding post 15 is retained in a position perpendicular with respect to the base 5.

The upper end of this post 15 is provided with an outstanding pointer 16 which depends from the arm 17 which is secured to the post 15 as at 18. This pointer 16 depends in front of the peripheral portion of the indicating disk 19 which has the degree markings 19 thereon. The pointer 16 is always just in rear of the bezel glass 20 which is located in the front wall 10.

Numeral 21 represents a block secured to the post 15 by bolts 22, which bolts also secure the depending plates 23 to opposite sides of the block 21 and as is shown in Figure 4, between the lower end portions of these plates 23 the gear 25 is rotatably mounted and this gear carries the weight or pendulum 25. The gear 24 meshes with the pinion 26 carried by the shaft 27 which is journaled through the plate 23 and also carries the indicating disk 19.

It can now be seen, that the base 5 can be placed against flat surfaces or curved surfaces such as pipes, etc., and as the weight 25 will always gravitate the disk 18 will be moved around as the gear 24 and pinion 26 are actuated so that the proper degree marking 19 will be visible through the bezel 20 in the proper relationship to the pointer 16.

While the foregoing specification sets forth the invention in specific terms, it is to be understood that numerous changes in the shape, size and materials may be resorted to without departing from the spirit and scope of the invention as claimed hereinafter.

Having thus described the invention, what is claimed as new is:

35 A grade indicator comprising a base, a post arising from said base, a cross-bar affixed centrally to one side of the post, a pair of front and rear bearing plates depending from said bar alongside said post, a rotary shaft extending 40 through the front plate and having a toothed pinion fast on the inner end thereof between said plates, a relatively larger counterweighted toothed pinion journaled in said plates below the first-mentioned pinion for rotation between 45 said plates and meshing with the first-mentioned pinion, a graduated disk fast on the outer end of said shaft in front of the front plate, and a pointer at the upper end of said post overlying the edge of the disk.

WILLIAM F. O'CONNOR.
